UNITED STATES PATENT OFFICE

94,281

DESIGN FOR A BUILDING WALL UNIT

Ivan Ročić, New York, N. Y.

Application October 4, 1934, Serial No. 53,482

Term of patent 3½ years

To all whom it may concern:

Be it known that I, Ivan Ročić, a citizen of the Kingdom of Croatia, Jugoslavia, and a resident of the city of New York, county of New York and State of New York, have invented a new, original, and ornamental Design for a Building Wall Unit, of which the following is a specification, reference being had to the accompanying drawing, forming part thereof.

Fig. 1 is a top perspective view of a building wall unit, showing my new design;

Fig. 2 is an end view; and

Fig. 3 is a sectional view taken in the position indicated on Fig. 1.

I claim:

The ornamental design for a building wall unit as shown.

IVAN ROČIĆ.
